ELECTRIC TOY TRACKAGE

Application filed March 31, 1930. Serial No. 440,245.

This invention relates to trackage for toy electric trains, such for instance as is contained in my Patent No. 1,636,416, July 19th, 1927, and in my pending application Serial No. 136,359, the present application being a continuation in part of said mentioned pending application.

An object of the present invention is to provide improved means whereby the passage of a train over a given section or sections of the track may be made to control the operation of auxiliary devices such as signals and the like.

A further object is to provide an electric toy track section intended to be attached to or removed from track forming relation with other electric toy track sections in the usual manner, said section being constructed to include improved means whereby the passage of a train over said section will complete a shunt circuit, in parallel with the train circuit, for controlling one or more auxiliary devices.

A further object is to provide an electric toy track section in which one of the wheel bearing rails is made to provide a contact to be engaged by the wheels of a passing train for controlling a shunt circuit in parallel with the train circuit but in which necessity for the use of insulating connecting means between said track rail and aligned rails of adjacent other toy track sections is dispensed with.

A further object is to provide an electric toy track section in which one of the wheel bearing rails is made to provide a contact to be engaged by the wheels of a passing train for controlling a shunt circuit in parallel with the train circuit but in which a conductive path is provided through said track section between the opposite ends of the mentioned track rail so that said path may carry the train circuit as for instance if for any reason the opposite wheel bearing rail does not provide a conductive path through the section for that purpose.

A further object is to so construct the electric toy section that the mentioned conductive path will be provided directly through

the wheel bearing rail which also provides said contact.

A further object is to provide an improved type of rail constructed for attachment to the cross ties of the electric toy section in the usual manner providing electric continuity between its opposite ends and having a contact portion extending longitudinally along its upper edge insulated from the remainder of the rail.

A further object is to provide means whereby to electrically connect together the contact portions of adjacent electric toy sections.

A further object is to so construct the electric toy section that it will serve its intended purpose in the system irrespective of which of its wheel bearing rails is connected in alignment with a given wheel bearing rail of the remainder of the system.

A further object is to so construct the electric toy section that electric conductors may be connected thereto at either or both sides thereof with equal facility.

A further object is to so construct the electric toy section that each of its two wheel bearing rails will have an insulated contact portion and so that the contact portions of the two rails will be electrically connected together.

A further object is to so construct the electric toy section that the usual detachable conductor attaching clip may be employed for connecting conductors to the rails thereof.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment in the invention:—

Fig. 1 is a diagrammatic plan view of an electric toy track system employing sections of the type with which this invention is concerned.

Fig. 2 is a top plan view of an improved toy track section constructed in accordance with this invention and showing the same in operative association with aligned rails of adjacent other toy track sections.

Fig. 3 is an enlarged side elevational view of the improved toy track section appearing in Fig. 2.

Fig. 4 is a transverse sectional view taken upon the plane of line IV—IV of Fig. 2.

Fig. 5 is a similar transverse sectional view taken upon the plane of line V—V of Fig. 2.

Fig. 6 is a detail sectional view through one of the rails of the section and illustrating a modification thereof.

Fig. 7 is a similar detail sectional view illustrating a further modification.

Fig. 8 is a top plan view showing two electric toy track sections connected together, said view illustrating a modification in the construction of the sections.

Fig. 9 is a diagrammatic transverse sectional view through one of the toy sections appearing in Fig. 8 being substantially upon the plane of line IX—IX of Fig. 8.

Fig. 10 is a similar sectional view but illustrating a further modification.

Fig. 11 is an enlarged transverse sectional view through one of the wheel bearing rails of the toy section appearing in Fig. 10.

Fig. 12 is a similar sectional view through the same rail as in Fig. 11, the section in this instance being substantially upon the plane of line XII—XII of Fig. 14.

Fig. 13 is a similar sectional view taken upon the plane of line XIII—XIII of Fig. 14, and

Fig. 14 is a fragmentary plan view showing portions of two adjacent toy track sections to illustrate their manner of connection.

Referring to the drawings for describing in detail the structure illustrated therein, and considering first the invention as illustrated in Figs. 1 to 5, the reference characters L and G indicate the two metallic wheel bearing rails of an electric toy track section, and the reference character H indicates the intermediate or "third" metallic rail of said section. These three separate rails are connected together by cross tie means, such as the three metallic cross ties 1, 2 and 3 as illustrated.

The intermediate or "third" rail is insulated from the other rails and from the cross ties by insulating members 4—4—4 as is customary.

The wheel bearing rail L as shown is not insulated from the cross ties. It is held in metallic contact with said cross ties as by means of the tangs 5—5 provided upon the cross ties for this purpose, and is hence in constant electrical connection with said cross ties.

The wheel bearing rail G is formed so that it provides an insulated wheel engaging por-

tion 6 arranged to serve as a contact which is adapted to be engaged by the wheels of a passing train for controlling a shunt circuit, in parallel with the train circuit, for operating one or more auxiliary devices, and to this end said rail G is illustrated in the present figures to be formed of three longitudinally extending members, one of said members as 7 being of metal and providing a conductive path throughout the length of the rail and having means at its opposite ends as at 8—8 by which to electrically and mechanically connect it with adjacent portions of aligned rails of other toy electric sections, another of said members being also of metal and providing the contact portion 6 for engagement by the car part, and the third member, as 9, being of insulating material arranged to electrically insulate the first two mentioned members from each other.

The member 7 provides an upstanding flange or web 10 for the rail and also the bottom flange as 11 of the rail which bottom flange is of the same proportions as is usual to the rails of toy electrical railways and is adapted to be fastened to the cross ties 1, 2 and 3 by the tangs 5—5 of the cross ties in the usual manner, as seen in Fig. 2.

At its opposite ends the member 7 is extended to provide sockets 12 for receiving the connector pins 8, the upper outer surface of said sockets 12 standing as parts of the wheel bearing surface of the rail.

The member 6 is provided with an upper transversely curved portion corresponding to the normal cross sectional contour of the wheel bearing portion of the rail and disposed so as to stand in continuation of the wheel bearing surfaces of the socket parts 12—12. It has a depending flange or web 13 standing parallel with and lapping the flange or web 10.

The insulating member 9 is interposed between the two flanges or webs 10—13 and is connected to each by means of suitable rivets or the like as 14, the rivets which fix the flange 13 to the insulating member being received in openings 15 of the flange 10, and the rivets which fix the flange 10 to the insulating member being of course received in similar openings provided in the flange 13, so that the flanges will thereby be effectively insulated from each other.

The member 9 not only serves to insulate the members 6 and 7 but also materially stiffens and re-enforces the rail.

An extension as 16 continues from the flange 13, in insulated relation, to the member 7 and serves as a suitable medium by which to attach a conductor to the member 6.

Any suitable means may be provided by which to connect a signal or like device, as 17, in circuit with the "third" rail H and with the contact portion 6 of the track rail G, and for this purpose the drawings illustrate a de-

vice consisting of a rectangular piece of insulating material as at 18 extending beneath the mentioned rails. A conductor element 19 carried by this insulating piece engages with the rail H, being preferably soldered thereto, and a similar conductor element 20 engages with the extension 16 of the contact member 6 being preferably soldered thereto. Two binding posts as 21 and 22 are carried by the insulating piece and these are connected with the conductors 19 and 20 respectively.

Conductors as 23 and 24 leading from opposite sides of the signal device 17 may be connected with the binding posts 21 and 22 as will be readily understood.

In Fig. 1 a plurality of electric toy track sections are diagrammatically illustrated as they appear when connected together for use. A source of electrical energy is indicated at 25 with a conductor 26 leading from one side thereof to the "third" rail G of the system, and with a conductor as 27 from its opposite side connected with the two wheel bearing rails L and G of the system, it being noted that although the conductor 27 is here shown as having direct connection with both of said wheel bearing rails it is usually sufficient to connect said conductor directly with only one of said rails, the current being fed to the other through the several metallic cross ties of the ordinary electric toy track sections as heretofore manufactured (see cross ties 1, 2 and 3 in Fig. 2).

In this system the several sections of track as illustrated are indicated by reference characters from 28 to 37 inclusive, the joints between said sections being clearly indicated. All of the sections illustrated, excepting the section indicated by the reference character 30, are of ordinary construction, the section 30 however being one of the improved sections in which the wheel bearing rail G is provided with the insulated wheel engaging or contact portion 6 as above described.

The signal device 17 is shown with its conductors 23 and 24 connected with the "third" rail and with the contact portion 6.

A train is illustrated as travelling along the system, said train having wheels 38—38 riding upon the wheel bearing rails and having a shoe 39 riding upon the "third" rail, the shoe being connected to one side of a train propelling motor 40, the opposite side of the motor being grounded upon the frame as 41 of the train and hence upon all of the wheels of the train.

The propelling circuit for the train is of the usual type well known in this art, namely from source 25 through conductor 26 to the "third", or power, rail of the system, through the shoe 39 and motor 40 to ground upon the frame of the train and back to the opposite side of the source through the train wheels and the wheel bearing rails.

The shunt circuit through the signal de-

vice 17 is closed as soon as one of the wheels of the train rides into engagement with the insulated portion 6 of the wheel bearing rail G of the improved section, said shunt circuit being traced as follows: From source 25 along the "third", or power, rail, to conductor 23, through the signal device 17 and back by way of conductor 24 to the insulated portion 6, and thence, by way of the wheel which is in engagement with said portion 6, to ground upon the frame of the train, the remainder of this circuit including the wheels of the train which bear upon portions of the two wheel-bearing rails outside of the insulated portion 6, and thence back along said wheel bearing rails to the opposite side of the source.

The rail L of the present improved section constitutes the "ground" rail of said section since in use it is in metallic contact with the wheel bearing rails of other sections to which it is operatively connected.

Concerning the improved electric toy track section disclosed, it is noteworthy that it provides for conductive paths through itself from both of the wheel bearing rails of other toy sections to which it may be connected as well as the usual separate path through the "third", or power, rail. By this arrangement all four of the joints for connecting the two wheel bearing rails of the improved section with the wheel bearing rails of adjacent other sections are made available for carrying the ground current through the improved section. If for any reason the wheel bearing rail L should not be in good conductive connection at one or both of its ends with aligned wheel bearing rails of other sections the conductive connection between the wheel bearing rail G and aligned wheel bearing rails of the other section at the ends of said rail G will continue to carry the current through the improved section.

It will be understood that the present improved track section is intended to be inserted between other sections in the same general manner and for the same purpose as is now well known in this art and fully set forth in my patent above referred to, and that when thus inserted it will, by the simple act of its insertion, provide a shunt circuit from the main car propelling circuit of the track system adapted to operate the auxiliary device 17 in parallel with the propelling motor of the car, that is, with the train circuit.

In the modification Fig. 6 it is proposed that if desired the separately formed member providing the contact portion 6 may have its flange portion 17 extended at opposite ends of the rail and shaped to provide sockets as 42 standing parallel beside the sockets 12 and adapted to receive metallic connecting pins similar to the pins 8 wherewith the contact member 6 may be readily electrically connected.

cally connected with a similar contact member present upon the next adjacent electric toy section. This is useful where two electric toy sections constructed in accordance with the present invention are to be connected together for increasing the length of track-age operable for controlling the signal device 17, and it is noted that by the arrangement just indicated the contact members 6 of the two improved sections will be electrically and mechanically connected without any other effort on the part of the operator than that which is ordinarily required for connecting together two electric toy sections, namely of simply inserting the connector pins of one section into the mating sockets of the adjacent section.

In the modification Fig. 7 it is suggested that if desired the wheel bearing rail G may be formed throughout its length of the general cross sectional contour similar to rails L and H, and the contact, or car part engaging, portion may be provided thereon as a separate tubular sheath here indicated as 43 gripping around the upper tubular bead shaped portion of the rail and insulated therefrom as by means of a tubular strip of insulating material as 44.

It will be understood that the members 43 and 44 may be made sufficiently thin so that they will not appreciably increase the exterior diameter of the wheel bearing portion of the rail, or if preferred the portion of the rail over which the members 43 and 44 are applied may be made of a relatively reduced diameter, as compared with the usual practice, so that the exterior sizes of the member 43 may be the same or nearly the same as the normal size of the upper portion of a rail, thus to bring the wheel engaging part of member 43 in proper tracking alignment with adjacent wheel engaging portions of the track.

The modification Figs. 8 and 9 illustrates an arrangement whereby the conductors for extending to signal devices or the like may be conveniently connected at either or both sides of the electric toy section, also whereby the electric toy section will serve its intended purpose in the system irrespective of which of its wheel bearing rails happens to be aligned with a given wheel bearing rail of the remainder of the system. According to this modification it is proposed that the improved electric toy section shall have both of its wheel bearing rails provided with insulated contact portions, instead of said insulated contact portion being provided upon only one of the wheel bearing rails as heretofore described.

As indicated in these figures the wheel bearing rails L and G are each of the same construction as heretofore described with respect to the wheel bearing rail G, and the rectangular piece of insulating material 18

is enlarged so as to extend entirely across the toy section and to carry an additional set of binding posts 21-22 at its opposite end, one set being at one side of the toy section and the other at the opposite side of the toy section, each adapted for the attachment of a signal or like device thereto in the same manner as heretofore referred to. The conductor 19 connects the "third" rail with both of the binding posts 21, and the conductor 20 connects together the contact portions 6 of rails L and G and connected both with the binding posts 22-22.

It will be understood that as soon as a train moves onto this section the shunt circuit through the signal device or devices 17 will be the same as heretofore described, it being noted however that current will flow from both of the contact portions 6 into the train wheels and thence through its ground connection on the train to one or more other train wheels which at the same time bear upon wheel bearing rails outside of the insulated portions 6.

This modification also suggests that the binding posts 22 of two adjacent sections may be conveniently utilized for the attachment of a connecting conductor as 45 by which to connect together the contact portions 6 of two adjacent electric toy sections of the type here described when it is desired to use more than one of said sections in connected relation. The conductor 45 may be used in lieu of the arrangement described with respect to the structure Fig. 6, or it may be used in addition to the connection afforded by the arrangement described with reference to Fig. 6, as an auxiliary thereto.

The modification Fig. 10 suggests an arrangement of parts whereby the usual detachable conductor attaching clips may be employed for connecting conductors to the rails of the present improved electric toy section, it being noted that these detachable conductor attaching clips, one of which is diagrammatically illustrated at 46 in Fig. 10 includes a rectangular piece of insulating material similar to that indicated 18 in Fig. 2 and having binding posts 21 and 22 thereon. Instead of being soldered to the rails however it has a hook portion as 47 for engaging a flange of the "third" rail H and a latch member 48 manually movable to engage a flange of one of the wheel bearing rails. In order to conveniently utilize this conductor attaching clip the modification Fig. 10 contemplates a re-arrangement of the parts of the wheel bearing rails as compared with the arrangement above described with respect to the previous figures. The rearrangement is illustrated in Figs. 11, 12 and 13 and from these it will be noted that the rail member as 49 providing the contact portion 6 provides a relatively outer flange as 50 at the lower edge of the rail while the rail mem-

ber as 51 which carries the end attaching members 8 provides a relatively inner flange as 52. This is desirable in that it enables the latch member 48 to engage about the flange 50 for thereby electrically connecting the binding posts 22 with the contact portion 6 by the simple act of attaching the conductor attaching clip in position in the same manner as is employed for attaching such clips to ordinary standard electric toy sections.

In order that the arrangement illustrated in Fig. 10 may have the advantages above pointed out with regard to the structure Figs. 8 and 9 it is suggested that both of the wheel bearing rails L and G may be constructed as illustrated in Figs. 11 to 13, that the rail members 49 shall be insulated from the two end cross ties 1 and 3 as by means of insulation 53, in Fig. 12, but that said rail members shall be in electrical engagement with the intermediate cross tie 2 as indicated in Fig. 11, also that the rail member 51 shall be in electrical engagement with the end cross ties 1 and 3 but shall be insulated from the intermediate cross tie 2 as by means of insulation 54, it being understood of course that the members 49 and 51 are insulated from each other by insulating member 9 in the same manner as heretofore described with respect to Figs. 1 to 5.

By this arrangement it will be seen that the contact portions 6 of the two wheel bearing rails are electrically connected together by the intermediate cross ties 2 while the rail members 51 are electrically connected together by the cross ties 1 and 3.

The detachable conductor attaching clips 46 may thus be moved from one side to the other of the track at the will of the operator, the connection being the same in either instance.

The member 49 may be extended so as to provide sockets as 55 at its opposite ends for receiving connector pins by which it may be connected with similar members of adjacent other toy sections in the same manner as referred to with respect to Fig. 6, and as more particularly illustrated in the drawings Figs. 13 and 14.

As many changes could be made in this construction without departing from the scope of the invention, as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. As an article of manufacture, an electric toy track section intended to be attached to or removed from track forming relation with other electric toy track sections in the

usual manner, said section being made up of spaced wheel bearing rails and an intermediate insulated third rail with cross-tie means by which all of the rails are mechanically connected together for unitary handling, at least one of the wheel bearing rails having opposite end wheel engaging portions of its length constructed and arranged for connection in track forming relation with aligned rails of adjacent other toy track sections, said mentioned rail having an intermediate portion of its length integral with said end portions electrically and mechanically connecting said end portions together, and said mentioned rail also having a wheel engaging portion formed as a member separate from the remainder of said rail and supported in insulated relation thereon intermediate said end wheel engaging portions and adapted thereby to serve as a contact to be engaged by the wheels of a passing train for controlling a shunt circuit in parallel with the train circuit.

2. As an article of manufacture, an electric toy track section intended to be attached to or removed from track forming relation with other electric toy track sections in the usual manner, said section being made up of spaced wheel bearing rails and an intermediate insulated third rail and cross-tie means by which all of the rails are mechanically connected together for unitary handling, at least one of the rails having opposite end portions constructed and arranged to serve in connecting said rail in track forming relation with aligned rails of adjacent other toy track sections, said mentioned rail having an intermediate portion of its length electrically and mechanically connecting said end portions together, and said mentioned rail also having a portion of itself formed as a member separate from the remainder of said rail and supported in insulated relation thereon adapted to be engaged by a part of a passing train thereby to serve as a contact to be engaged by a current carrying part of a passing train for controlling a shunt circuit in parallel with the train circuit.

3. A rail for toy electric track sections, said rail being built up of a plurality of separately formed members, one of said members being of conductive material arranged to provide a conductive path through the rail from end to end of the rail, another of said members being of conductive material arranged to provide a car part engaging head portion for said rail, and another of said members being of insulating material arranged to electrically insulate said first two mentioned members from each other, together with means to mechanically connect said members in rail forming relation, and means by which to detachably electrically and mechanically connect opposite end portions of the first mentioned member in track forming relation with aligned other track rails.

4. As an article of manufacture, an electric toy track section intended to be attached to or removed from track forming relation with other electric toy track sections in the usual manner, said section being made up of spaced wheel bearing rails and an intermediate insulated third rail with cross-tie means by which all of the rails are mechanically connected together for unitary handling, said third rail and at least one of the wheel bearing rails having means at their ends by which they may be detachably, mechanically and electrically connected in tracking alignment with corresponding rails of adjacent other toy track sections and each being constructed so as to provide a separate path of conductivity between its opposite ends, and one of the rails of said section also having a car part engaging head portion formed as a member separate from the remainder of said rail and supported in insulated relation thereon adapted thereby to serve as a contact to be engaged by a part of a passing train for controlling a shunt circuit in parallel with the train circuit.

5. A rail for toy electric track sections, said rail being built up of a plurality of separately formed members, connected together in rail forming relation and having means at its opposite ends by which it may be detachably connected in tracking alignment with adjacent other toy track rails, one of said members being of conductive material arranged to provide a conductive path through the rail from end to end of the rail, another of said members being of conductive material arranged to provide a car part engaging head portion for said rail, and another of said members being of insulating material arranged to electrically insulate said first two mentioned members from each other.

6. As an article of manufacture, an electric toy track section intended to be attached to or removed from track forming relation with other electric toy track sections in the usual manner, said section being made up of spaced wheel bearing rails and an intermediate insulated third rail with cross-tie means by which all of the rails are mechanically connected together for unitary handling, at least one of the wheel bearing rails having a bottom flange portion extending longitudinally thereof by which it is connected with the cross-tie means, said wheel bearing rail also having an upper portion providing a wheel engaging surface extending longitudinally along the top edge of the rail parallel above said bottom flange portion, means whereby said upper portion is insulated from the remainder of the rail, a pair of wire terminals, a conductor extending from said mentioned upper portion into connection with one of said wire terminals, and a second conductor connected with the mentioned third rail and extending into connec-

tion with the second wire terminal, all whereby the upper portion of the mentioned wheel bearing rail is adapted to serve as a contact to be engaged by the wheels of a passing train for controlling an electric circuit including said wire terminals.

7. As an article of manufacture, an electric toy track section intended to be attached to or removed from track forming relation with other electric toy track sections in the usual manner, said section being made up of spaced wheel bearing rails and an intermediate insulated third rail with cross-tie means by which all of the rails are mechanically connected together for unitary handling, at least one of the wheel bearing rails having a bottom flange portion extending longitudinally thereof by which it is connected with the cross-tie means, said wheel bearing rail also having an upper portion providing a wheel engaging surface extending longitudinally along the top edge of the rail parallel above said bottom flange portion, said upper portion having a part projecting downwardly therefrom in lapping relation with a part projecting upwardly from the bottom flange portion, and an insulating member interposed between said lapping parts and fixed thereto, whereby the mentioned upper portion of the mentioned wheel bearing rail is insulated from the remainder of said rail and adapted thereby to serve as a contact to be engaged by the wheels of a passing train for controlling an electric circuit.

8. A rail for toy electric track sections, said rail being built up of a plurality of separately formed members, one of said members being of conductive material extending from end to end of the rail and having sockets at its opposite ends adapted to serve in connecting the rail in tracking alignment with adjacent other rails, another of said members being of conductive material providing a car part engaging surface extending longitudinally along the top edge of the rail and having a longitudinally extending portion lapping a similarly longitudinally extending portion of the first member, and another of said members consisting of a strip of insulating material interposed between the lapping portion of the first two mentioned members to insulate said two members from each other, together with means to mechanically connect all of said members in rail forming relation.

9. As an article of manufacture, an electric toy track section intended to be attached to or removed from track forming relation with other electric toy track sections in the usual manner, said section being made up of spaced wheel bearing rails and an intermediate insulated third rail with cross-tie means by which all of the rails are mechanically connected together for unitary handling, at least one of

the wheel bearing rails having opposite end portions constructed and arranged to serve in connecting said rail in track forming relation with aligned rails of adjacent other toy

5 track sections, said mentioned rail having an intermediate portion of its length electrically and mechanically connecting said end portions together, and said mentioned rail also having a wheel engaging portion of itself 10 formed as a member separate from the remainder of said rail and supported in insulated relation thereon adapted thereby to serve as a contact to be engaged by the wheels of a passing train for controlling a shunt circuit 15 in parallel with the train circuit, together with means provided upon said insulated wheel engaging portion by which it may be detachably electrically connected with insulated wheel engaging portions of adjacent 20 other toy track sections.

10. As an article of manufacture, an electric toy track section intended to be attached to or removed from track forming relation with other electric toy track sections in the 25 usual manner, said section being made up of spaced wheel bearing rails and an intermediate insulated third rail with cross-tie means by which all of the rails are mechanically connected together for unitary handling, at least one of the wheel bearing rails 30 having a bottom flange portion extending longitudinally thereof by which it is connected with the cross-tie means, said wheel bearing rail also having an upper portion providing 35 a wheel engaging surface extending longitudinally along the top edge of the rail parallel above said bottom flange portion, means whereby the upper portion of the mentioned wheel bearing rail is insulated from the remainder of said rail and adapted thereby to 40 serve as a contact to be engaged by the wheels of a passing train for controlling an electric circuit, and said bottom flange portion and said insulated upper portion each having 45 sockets provided in their opposite ends adapted to receive connecting pins whereby said 50 portions respectively may be detachably, mechanically and electrically connected with the corresponding portions of adjacent other toy 55 track sections.

11. As an article of manufacture, an electric toy track section intended to be attached to or removed from track forming relation with other electric toy track sections in the 60 usual manner, said section being made up of spaced wheel bearing rails and an intermediate insulated third rail with cross-tie means by which all of the rails are mechanically connected together for unitary handling, all of 65 said rails having opposite end portions by which they may be detachably, mechanically and electrically connected in track forming relation with the corresponding rails of adjacent other toy track sections and the section being constructed so that the two end 70

75 portions of each of the wheel bearing rails respectively are independently electrically connected together thereby providing two separate paths of conductivity through the toy section, one path for each wheel bearing rail, each of the wheel bearing rails having an insulated wheel engaging portion adapted to serve as a contact to be engaged by the wheels of a passing train for controlling an electric circuit, and the insulated wheel engaging portions of the respective wheel bearing rails each having means at their opposite ends adapted to receive connecting pins whereby said portions respectively may be detachably, mechanically and electrically connected with the corresponding portions of adjacent other toy track sections. 80

12. As an article of manufacture, an electric toy track section intended to be attached to or removed from track forming relation with other electric toy track sections in the usual manner, said section being made up of spaced wheel bearing rails, and an intermediate insulated third rail with cross-tie means by which all of the rails are mechanically connected together for unitary handling, all of said rails having opposite end portions by which they may be detachably, mechanically and electrically connected in track forming relation with the corresponding rails of adjacent other toy track sections and the sections being constructed so that the end portions of both of the wheel bearing rails are electrically connected together, each of the wheel bearing rails having an insulated wheel engaging portion adapted to serve as a contact to be engaged by the wheels of a passing train for controlling an electric circuit, two pairs of wire terminals one pair adjacent each wheel bearing rail, and said section being constructed to electrically connect the insulated wheel engaging portions of the two wheel bearing rails with one terminal of each pair and to electrically connect the third rail with the other terminal of each pair. 100

13. A rail for toy electric track sections, said rail being built up of a plurality of separately formed members one of said members being of conductive material extending longitudinally of the rail and having a flange projecting laterally at one side along the bottom edge of the rail, another of said members being of conductive material providing a car part engaging portion for the rail also extending longitudinally of the rail and having a flange projecting laterally therefrom along the bottom edge of the rail opposite to the first flange, and another of said members being of insulating material fixed to the first 115 two members and interposed between them so as to insulate them from each other, the first mentioned member having a pair of car part engaging portions one at each of its ends, and the car part engaging portion of 120 125 130

the second mentioned member being arranged intermediate the two car part engaging portions of the first member and in tracking alignment therewith.

14. As an article of manufacture, an electric toy track section intended to be attached to or removed from track forming relation with other electric toy track sections in the usual manner, said section being made up 10 of spaced wheel bearing rails and an intermediate insulated third rail with cross tie means by which all of the rails are mechanically connected together for unitary handling, and a member mounted upon one of 15 said rails by gripping around the head portion of said rail in insulated relation thereto adapted to serve as a contact to be engaged by a passing car part for controlling a shunt circuit in parallel with the train circuit, said 20 contact being positioned to stand in interposed relation between the rail head and the passing car part.

15. A rail for toy electric track sections, said rail being built-up of a plurality of separately formed members connected together in rail forming relation, one of said members being of conductive material arranged to provide a conductive path through the rail from end to end of the rail and having means 25 at its opposite ends by which it may be detachably connected in tracking alignment with adjacent other toy track rails, another of said members being of conductive material adapted to serve as a contact and being 30 arranged for travel therealong of a part of a passing car, and another of said members being of insulating material arranged to electrically insulate the first two mentioned 35 members from each other.

16. A rail for toy electric track sections, said rail having a head portion, a web portion, and a flange portion, the head portion being made up at least in part of a member formed separate from the remainder of the 40 rail and providing a conductive contact forming surface along and in engagement with which a car part may travel, said flange portion being made up at least in part of a member of conductive material formed separate 45 from the remainder of the rail and providing means by which the rail may be connected with the cross ties of the track section, said web portion being made up at least in part of a member of insulating material arranged 50 to insulate the mentioned head forming member from the remainder of the rail, and said web and flange portions including a part which provides a conductive path through the rail from end to end of the rail and which 55 has means at its opposite ends by which said rail may be detachably connected in tracking alignment with adjacent other toy track rails.

17. A rail for toy electric track sections, said rail having a head portion, a web por-

tion, and a flange portion, the head portion being made up at least in part of a member formed separate from the remainder of the rail and providing a conductive contact forming surface substantially vertically above the 70 web portion along and in engagement with which a car part may travel, said flange portion being made up at least in part of a member of conductive material formed separate from the remainder of the rail and providing means by which the rail may be connected with the cross ties of the track section, the web portion standing substantially vertically between the flange and the head portions and there being insulating means arranged to 75 insulate the mentioned head forming member wholly from the flange portion of the rail.

18. A rail for toy electric track sections, said rail having an upper portion along and in engagement with which a car part may travel and a lower portion by which the rail may be connected with cross ties of the track section, and said upper portion being made up to include a contact strip longitudinally thereof arranged to be engaged by the traveling car part, together with insulating means by which said contact strip is insulated from the lower portion of the rail.

19. A built-up rail for toy electric track sections, said rail comprising two longitudinally extending parts connected together in insulated relation and co-operating to support a car which may travel along said rail, each of said two parts being of a character to serve as a conductor between the opposite 100 ends of the rail, one of said parts being arranged to serve as a contact to be engaged by a portion of a passing car, and each of said two parts having means at its opposite ends by which it may be electrically connected in aligned relation with similar insulated rail forming parts of adjacent other toy track sections.

20. A rail for toy electric track sections, said rail being built up of a plurality of separately formed members, one of said members being of conductive material extending longitudinally of the rail and having a flange projecting laterally at one side along the bottom edge of the rail, another of said members being of conductive material providing a car part engaging portion for the rail also extending longitudinally of the rail and having a flange projecting laterally therefrom along the bottom edge of the rail opposite to the first flange, and another of said members being of insulating material fixed to the first two members and interposed between them so as to insulate them from each other, the first mentioned member having a pair of car part engaging portions one at each of its ends, and the car part engaging portion of the second mentioned member being arranged intermediate the two car part engaging portions of the first member and in tracking 110 115 120 125 130

- alignment therewith and both said first and second mentioned members having means at their opposite ends by which they may be electrically connected in aligned relation 5 with similar members of adjacent other toy track sections.
21. A rail for toy electric railroad track, said rail having upper and lower longitudinally extending portions and a member of 10 conductive material fitting as a cover over said upper portion and insulated therefrom of a character to serve as a contact for engagement by a current carrying part of a car passing along said rail.
22. A rail for toy electric railroad track, said rail having upper and lower longitudinally extending portions, the upper portion including a relatively enlarged longitudinally extending head, and a contact strip of 15 conductive material fitted as a cover about said head and being held thereto in insulated relation by gripping around said head and an interposed insulating strip.
23. A rail for toy electric railroad track, 25 said rail having upper and lower longitudinally extending portions and a member of conductive material fitting as a cover over said upper portion and insulated therefrom of a character to serve as a contact for engagement by a current carrying part of a car passing along said rail, together with an extension formed upon said member extending away from said head adapted for the attachment of a conductor to said member.
24. A built-up rail for toy electric track sections, said rail comprising a strip of insulating material and two strips of conductive material connected together in rail forming relation, one of the strips of conductive material being shaped to provide connecting means at opposite ends of the rail for connecting to adjacent aligned rails of other sections, also conductor means between said end connecting means, also flanges at opposite sides of the rail and also a web portion, the other strip of conductive material being shaped to provide a portion serving as a contact for engagement by a car part traversing the rail and also a web portion, and the strip of insulating material being sandwiched between the two mentioned web portions and connected firmly therewith.
25. A built-up rail for toy electric track sections, said rail comprising a strip of insulating material and two strips of conductive material connected together in rail forming relation, one of the strips of conductive material being shaped to provide connecting means at opposite ends of the rail for connecting to adjacent aligned rails of other sections, also conductor means between said end connecting means, also a flange at one side of the rail and also a web portion, the other strip of conductive material being shaped to provide a flange at the opposite side of the rail also a portion serving as a contact for engagement by a car part traversing the rail and also a web portion, and the strip of insulating material being sandwiched between the two mentioned web portions and connected firmly therewith.
26. A built-up rail for toy electric track sections, said rail comprising a strip of insulating material and two strips of conductive material connected together in rail forming relation, one of the strips of conductive material being shaped to provide connecting means at opposite ends of the rail for connecting to adjacent aligned rails of other sections, also conductor means between said end connecting means, also a flange at one side of the rail and also a web portion, the other strip of conductive material being shaped to provide a flange at the opposite side of the rail, also a portion serving as a contact for engagement by a car part traversing the rail and also connecting means at its opposite ends spaced from the first mentioned connecting means adapted for connecting to adjacent aligned contact portions of other track sections and also a web portion, and the strip of insulating material being sandwiched between the two mentioned web portions and connected firmly therewith.
27. As an article of manufacture, an electric toy track section intended to be attached to or removed from track forming relation with other electric toy track sections in the usual manner, said section being made up of spaced wheel bearing rails and an intermediate insulated third rail with cross tie means by which all of the rails are mechanically connected together for unitary handling, and at least one wheel bearing rail including, as one part, a conductor continuous between the opposite ends of the section and forming the relatively inner flange of said rail and, as another part, an insulated contact disposed to be engaged by a passing car part and having a portion forming the relatively outer flange of said rail in position to be engaged by a connector device.
28. As an article of manufacture, an electric toy track section intended to be attached to or removed from track forming relation with other electric toy track sections in the usual manner, said section being made up of spaced wheel bearing rails and an intermediate insulated third rail with cross tie means by which all of the rails are mechanically connected together for unitary handling, and said section being reversible end for end so that either of its wheel bearing rails may be placed in tracking alignment with a given wheel bearing rail of the system according to the end for end position of the section, and each wheel bearing rail of said section being constructed to provide a through conductor forming the relatively inner flange of said rail and an insulated contact forming the rel-

atively outer flange of said rail, said insulated contacts being in position so that one thereof will be engaged by a vehicle wheel travelling along said given wheel bearing rail of the system regardless of the end for end position in which the section may be placed in the system.

In testimony whereof I affix my signature.
L. GESSFORD HANDY.
